TISSUE DISPENSER

Lawrence H. Muesing, 456 Frontage Road,
Northfield, Ill.

Filed Nov. 18, 1963, Ser. No. 77,451

Term of patent 14 years

(Cl. D52—2)

I claim:

The ornamental design for a tissue dispenser, substantially as shown.
